UNITED STATES PATENT OFFICE.

NOAH E. ROYER, OF EMPIRE, CALIFORNIA.

APPARATUS FOR AUTOMATICALLY SUPPLYING AND HEATING WATER FOR VARIOUS USES.

1,248,725.

Specification of Letters Patent.

Patented Dec. 4, 1917.

Application filed June 28, 1916. Serial No. 106,448.

To all whom it may concern:

Be it known that I, NOAH E. ROYER, a citizen of the United States, residing at Empire, in the county of Stanislaus and State of California, have invented new and useful Improvements in Apparatus for Automatically Supplying and Heating Water for Various Uses, of which the following is a specification.

10 This invention relates to apparatus for heating water and for generating steam for general uses, such as washing various articles, sterilizing vessels or receptacles, preserving and canning different articles of 15 food, and for cleansing fabrics. One object of the invention is to provide a comparatively simple apparatus having an automatic operation to control the ingress of water thereto from a supply main and to 20 maintain a uniform level in accordance with a predetermined adjustment in a containing receptacle constituting one of the essential features of the invention and operating as the prime means for effecting the several 25 uses and applications of the apparatus, and also to utilize in connection with a heating means a water circulating system relatively to the container and whereby the water may be maintained at the temperature desired 30 and necessary to carry on the several operations for which the improved apparatus is adapted.

The invention consists in the preferred construction and arrangement of the several 35 parts and the subcombinations of these parts which will be more fully hereinafter described and claimed.

In the drawings:

40 Figure 1 is a side elevation of an apparatus embodying the features of the invention, parts thereof being broken away and in section.

Fig. 2 is an end elevation of the apparatus showing parts thereof in section.

45 Fig. 3 is a transverse vertical section taken in the plane of the line 3—3, Fig. 1.

Fig. 4 is a horizontal section taken in the plane of the line 4—4, Fig. 3, and showing a part of the container.

50 Fig. 5 is a transverse vertical section through a water jacket surrounding and forming a part of one of the heaters.

Fig. 6 is a horizontal section taken in the plane of the line 6—6, Fig. 5.

55 Fig. 7 is a detail horizontal section of a portion of the heater taken through the bowl

thereof and showing a modification in the form of the water jacket.

The numeral 5 designates a container or receptacle which may be of any dimensions 60 and general contour, but which as shown is preferably of rectangular form to adapt the same to a large heating surface or so that the bottom 6 thereof may give a large heating expanse for effectively heating the 65 water admitted to the container or receptacle for carrying on the several operations for which the improved apparatus is adapted. The container or receptacle 5 is also preferably of large dimensions so that it 70 may have considerable capacity; and removably applied to the top of the container or receptacle 5 is a deep cover 7 having openings or outlets 8 therein which have co-operating valves or pivoted dampers 9 for 75 a purpose which will be presently explained. The container or receptacle 5 will be heated from a suitable source of heat generation, or the water that is fed thereto may be given the proper heat by any means adapted 80 for the purpose, and one practical heating apparatus is shown particularly by Fig. 1 and comprises a supporting frame 10 with a top 11 on which the container or receptacle 5 is disposed. Within the frame 10 two 85 heaters 12 of the oil or gas type are shown and provided with bowls, as at 13, see Figs. 6 and 7. The bowls 13 extend upwardly within the frame as shown and are surrounded by outer jackets 14 which form 90 with the bowls water spaces 15; and through the jackets and bowls are openings 16 closed by doors 17 having transparent panels 18 of any suitable form. The openings 16 are large enough to remove and replace the 95 burners of the heaters 12 and the latter are supplied with fuel by means of a pipe 19 running from a source of supply, as at 20. The water jackets around the bowls 13 operate similarly to a water back and are 100 braced by vertically disposed spaced rods 21 secured to the inner surface thereof by any suitable means, these rods extending from points above the bottom to points near the top of the jackets, as shown by Fig. 5. 105 The rods 21 are dispensed with at the fronts of the bowls and jackets so as to avoid interference with the formation of the openings 16 for giving access to the burners within the bowls 13. From the lower portion of each jacket 14 a circulating pipe 22 extends upwardly through the lower por- 110

tion of one side of the container or receptacle 5 close to the bottom 6 of the latter, and from the top of each jacket to a point some distance above the point of connection 5 of the pipe 22 with the container a second circulating pipe 23 is arranged so that water of a low temperature may be taken from the bottom of the receptacle or container 5 and fed into the lower or bottom portion of each 10 jacket and the heated water taken from the top of each jacket and fed into the container or receptacle at a point some distance above the bottom 6 of the latter and thereby provide a heating circulation relatively to the water to maintain the water in the container or receptacle at the proper temperature to perform the work desired.

Water is supplied to the container or receptacle 5 by automatically operating devices 20 which will now be particularly described. Connected to one end of the container or receptacle 5 is an inlet pipe 24 extending from a T-coupling 25 having a vertical supply connection 26 depending therefrom and 25 also connected to a lower T-coupling 27 in turn connected by a branch pipe or nipple 28 opening into a further T-coupling 29 on the upper end of a supply pipe 30 which may run from a water main or other water 30 source. The lower extremity of the supply connection 26, as shown by Fig. 2, is reduced in the form of a valve seat 31, and in the lower end of the T-coupling a plug 32 is fitted and rendered removable by the screw-threaded connection thereof as shown, said plug having a vertical bore 33 extending partially therethrough and opening out at the top thereof. Secured to the top of the T-coupling 25 is a guide plug 34 having a 35 bore therethrough as at 35; and movably extending through this guide plug 34, the T-coupling 25 and valve seat 31 is an elongated valve stem 36 having a valve 37 mounted thereon and engaging screw- 40 threads 38, as shown by Fig. 3, and held in place by suitable nuts 39 engaging the upper and lower ends thereof. The lower extremity of the valve stem 36 is vertically movable in the bore 33 of the plug 32, and the guide 45 plug 34 has an upper packing gland 40 to prevent leakage around the valve stem 36 working therein. Connected to the T-coupling 29 at the extremity thereof opposite to the connection or nipple 28 is a supporting connection 41 in the form of a hollow plug closed at one end, as clearly shown by 50 Fig. 3, and this supporting connection also engages a T-coupling 42 from which a pipe 43 extends inwardly and upwardly to the bottom 6 of the container or receptacle 5, as shown by Figs. 1 and 4. Rising from the upper end of the T-coupling 42 is a standard or fulcrum support 44 adjacent to the end of the container or receptacle 5 and engages the 55 center of an outstanding brace or arm 45,

and in the upper end of the standard or support 44 is a closing screw stem 46 with an upper bifurcated end 47 which forms the intermediate fulcrum means for a rocking lever 48, the lever being pivoted in the bifurcated end 47 of the stem 46, as at 49. The valve stem 36 is movably attached to one end of the rocking lever 48 and to the same end the upper terminal of a spring 50 is attached and extends downwardly and is secured to the connection or nipple 28 as shown by Fig. 3. Adjustably mounted on the opposite end of the rocking lever 48 is a tubular support or stem 51 which is fully open throughout its length and is connected to the center of the top dome 52 of a gravitating controller 53 which is in the form of a supplemental tank and has a flexible pipe 54 connected to and opening in at the bottom thereof and also connected to the lower portion of the T-coupling 42 so that there is a direct communication between the controller 53 and the bottom of the container or receptacle 5 by means of the pipes 54 and 43 and the T-coupling 42. The supporting stem 51 of the controller 53 is mounted in a guide 55 secured on the end of the rocking lever 48 and provided with a set-screw 56 whereby the adjustment of the said stem 51 and controller 53 may be fixed to regulate the operation of the apparatus as desired. The controller 53 may rise and fall or be adjusted without the least interference with the supply of water thereto in view of the fact that the pipe 54 is flexible and is primarily given 100 such length as to accommodate all operative and adjusted conditions. Projecting outwardly from the T-coupling 27 is a faucet 57 whereby cold water may be used from the apparatus or drawn from the cold water supply for any purpose desired, and in like manner a faucet 58 extends outwardly from the T-coupling 42 to provide for the use of hot water.

A rack 59 is adapted to be removably arranged in the container or receptacle 5 to support bottles, jars or other utensils above the water level to heat the contents of the bottles, jars, etc. or to sterilize the latter, or in some instances to cleanse the same. The 110 rack 59 may be of any approved structure and is preferably made of wire of suitable 115 gage and strength.

The operation of the apparatus is as follows: The controller 53 is primarily set by 120 adjusting the stem 51 thereof relatively to the rocking lever 48 to obtain the level of water desired in the container or receptacle 5, and the water is then permitted to run into the container from the supply pipe 30 125 by way of the nipple or connection 28, T-coupling 27, valve seat 31, supply connection 26, T-coupling 25 and pipe 24, and from the container the water passes by way 130 of the pipes 22 into the jackets or water

spaces 15 of the heaters and then back through the pipes 23 into the container, the valve 37 remaining open through the tension of the spring 50 attached to the end 5 of the lever 48 at the point adjacent to the attachment of the valve stem 36 to said lever. The tension of the spring 50 is sufficient to overcome considerable water weight in the controller 53 and the controller and 10 its stem combined. When the water has reached a predetermined level in the container or receptacle 5 a similar level of the water will be effected in the controller 53 as the said controller is fed by the pipe 43 connecting with the T-coupling 42 and the pipe 54 attached to the bottom of the controller. When the desired level of water has been reached in the container the quantity of 15 water in the controller will then be of such weight as to automatically overcome the resistance of the spring 50 and the said controller and its stem 51 together with the end of the rocking lever 48 to which the said stem is attached will depress, thereby 20 elevating the opposite extremity of the said rocking lever and pulling upwardly on the valve stem 36 to bring the valve 37 closely against the valve seat 31 and shut off the supply of water to the container or 25 receptacle 5. As the water vaporizes or steams and gradually diminishes in the container or receptacle 5 the water in the controller 53 will similarly diminish, the water level both in the controller and the container being at all times uniform. When 30 the water in the container and the controller diminishes to such an extent that the weight of the controller 53 by reason of the diminished quantity of water therein will be overcome by the spring 50, the said controller and its stem will be elevated through the 35 action of said spring and the valve stem 36 lowered and the valve 37 opened to again supply the container or receptacle 5 with 40 water from the supply pipe 30. This operation will regularly ensue as long as it is desired to have the apparatus active and various cleansing and sterilizing operations 45 may be carried on in the container or receptacle or the said container may be used as 50 a boiler or cleansing means for fabrics or other articles. The improved apparatus is particularly useful and convenient in dairies for sterilizing milk bottles, cans and other 55 utensils that have been used as milk containers, and the cans may be thoroughly sterilized and cleansed by turning the same upside down on the cover 7 over the openings or vents 8 after first shifting the valves or 60 dampers 9 to uncover said openings, as clearly shown by Fig. 2. Milk pails may be similarly disposed on the top of the cover 7 as shown by Fig. 2. The valves or dampers 9 are closed only long enough over the 65 openings or vents 8 to permit the water to

heat more rapidly, but when water reaches a degree of heat where steam may be generated and accumulate above the water level, the openings or vents 8 are opened so as to permit the steam to escape and avoid pressure on the water and a consequent modification of the water level in the controller, the openings or vents 8 being exposed to a degree in proportion to the amount of steam within the receptacle. The openings or 70 vents 8 may be uncovered without in the least detracting from the efficiency of the operation sought in cleansing or sterilizing articles that may be placed on the rack within the receptacle. When articles are placed 75 on the top of the cover 7 the openings or vents 8 may be fully uncovered so as to permit a free outflow of the steam from the interior of the receptacle 5 to sterilize and cleanse cans, pails or other devices disposed 80 on the said cover. It is proposed to use the apparatus for any purpose to which it may be applicable other than for the particular services mentioned, and also to vary the proportions, dimensions and minor details 85 of the several parts. It is also preferred that all of the parts of the apparatus be constructed of metal except the pipe 54 and that said metal be of a non-corrosive character. It will be seen that the container or 90 receptacle 5 may be readily cleansed as it is freely accessible by removing the cover 7, and as shown by Fig. 7 the water jacket feature may be applied to the heater bowls 95 13 without utilizing a part of the bowls as 100 the inner wall of the jacket, and in this particular structure of the water jacket an approximately crescent-shaped partial inclosure 105 60 is provided to fit over a portion of the bowl as shown and having the rod reinforcements 61 vertically extending therethrough, the pipes 22 and 23 being connected in substantially the same manner as heretofore explained. By this means the apparatus 110 may be applied in operative relation to various forms of heaters and permit said heaters to be used for purposes other than means for heating the water in the improved apparatus.

What is claimed is:

1. In an apparatus of the class specified, a container having a cover with vapor vents, heating means for the container, water feeding means attached to the container above the bottom of the latter, water outlet means secured to the bottom of the container cut off from communication with the water feeding means, automatically operating devices comprising a valve disposed in the water feeding means, and a freely suspended gravitating water containing controller connected to said valve for operating the latter, and a connection interposed between the controller and this outlet means whereby the controller is rendered sensitively oper- 115
- 120
- 125
- 130

ative in accordance with the amount of water in the container, the container having no other continuously open outlet except that connected to the controller and the 5 vapor vents of the cover.

2. In an apparatus of the class specified, a container having a cover with vapor vents and provided with heating means, water supply connections attached to the container 10 above the bottom of the latter and including a valve for regulating the inlet of the water to the container, water outlet means attached to the bottom of the container and cut off from communication with the water 15 supply connections and serving as the sole continuously open outlet for the container, and a suspended water containing gravitating controller movably connected to the valve in the supply connections and having 20 a flexible pipe connection from the bottom thereof to the water outlet means, the water outlet means from the container causing the water to flow solely into the bottom of the gravitating controller to modify the weight 25 of the latter and whereby when the water reaches a certain level in the container the supply of the container will be shut off, the container having no other continuously open outlet than by way of the gravitating controller and the vapor vents of the cover.

3. In an apparatus of the class specified, a water container provided with means for heating water therein, water supply means connected to the container above the bottom 35 thereof, an outlet pipe connected to the bottom of the container, and means for automatically supplying water to and maintaining the water at a predetermined level in the container and including a valve controlling the supply of water to the container and provided with an upwardly projecting stem, a rocking lever to one end of which the valve stem is movably attached, a water 40 receiving gravitating controller suspended 45 from the opposite end of the lever and consisting of a hollow body having a pipe connected to the bottom thereof and to the water outlet pipe for the container, means for adjustably connecting the controller to 50 the rocking lever, and a spring connected to the rocking lever adjacent to the point of attachment of the valve stem thereto and to another portion of the apparatus.

4. In an apparatus of the class specified, 55 a container provided with water heating means, water inlet and outlet pipes respectively connected to the container above the bottom thereof and to the bottom of the same, the water outlet pipe being cut off 60 from communication with the water inlet pipe, a water supply connected to the inlet pipe and provided with a valve, and a hollow gravitating controller suspended for

free operation and connected to the valve of the water supply, said controller having 65 a pipe connected to the bottom thereof and to the outlet pipe of the container to permit the water to have a continuously open outlet solely from the container into the controller to maintain the water level in the 70 controller and container always the same, the vapor escaping through the vents of the cover, the controller being vertically adjustable to modify the time of operation thereof, a variation in the weight of the 75 controller and water therein by reason of the evaporation of the water in the container due to heat regulating the supply of water to the container.

5. In an apparatus of the class specified, 80 a container provided with water heating means, water supply devices connected to the container and including a valve with a stem, water outlet devices connected to the bottom of the container, a hollow gravitating controller having a pipe connected to the bottom thereof and to a part of the water outlet devices and also provided with a venting stem extending upwardly from the top thereof and adjustably associated 85 with the stem of the valve of the water supply devices, and means for overcoming the 90 normal weight of the controller to permit the valve of the water supply devices to remain open until the weight of the controller and water therein exceeds the resistance 95 of the said means for overcoming the normal weight of the controller.

6. In an apparatus of the class specified, 100 a container provided with water heating means, water supply devices connected to the container above the bottom of the latter and including a valve with a stem, water outlet devices connected to the bottom of the container, a rocking lever having one extremity connected to the stem of the said valve, a hollow gravitating controller having a flexible pipe connected to the bottom thereof and to a part of the water outlet 105 devices and also provided with an upwardly extending tubular venting stem adjustably associated with the extremity of the lever opposite to that connected to the valve stem to automatically operate the said valve, and means for overcoming the normal weight of 110 the controller to permit the valve to remain open until the weight of the controller and water therein exceeds the resistance of the 115 said means.

In testimony whereof I have hereunto set 120 my hand in presence of two subscribing witnesses.

NOAH E. ROYER.
